CONTROL MECHANISM

William Pechy, Manasquan, N. J., assignor to
 American Can Company, New York, N. Y., a
 corporation of New Jersey

Application July 22, 1943, Serial No. 495,783

5 Claims. (Cl. 192—127)

This invention relates to feeding mechanism for advancing sheet material along a path of travel and has particular reference to a rotary gauging device for testing the thickness of the sheets to detect abnormally thick sheets and sheets which stick together, the device immediately stopping the mechanism upon detection of such sheets so that they may be removed.

The instant invention contemplates a sheet gauging and stopping mechanism connected with an intermittently operating sheet feeder and includes a rotary device which gauges a sheet while it is at rest and determines the sheet thickness at a definite position on the sheet's surface which position may be located at a work station of a machine the mechanism allowing passage only of sheets having a normal, predetermined thickness.

An object of the invention is the provision in an intermittent feeding mechanism of a sheet thickness gauging device and stop mechanism for detecting and stopping the feeding of sheets having abnormal thickness and of sheets which stick or adhere together and which otherwise are fed as one, such device constituting a continuously rotating gauge which is so formed as to operate only against the surface of a sheet while the sheet is at rest.

Another object is the provision of such a mechanism wherein the thickness gauging device, cooperating with a movable stop member, calipers successive sheets advanced along a path of travel, allowing sheets of normal gauge thickness to pass but deflecting sheets of abnormal thickness and double sheets sticking together, such deflection being had on an edge of the passing sheet, when such edge comes into engagement with and moves a detector lever to interrupt the feeding of the sheets, further feeding action being stopped until the abnormal or double sheet condition is cleared from the mechanism.

Numerous other objects and advantages of the invention will be apparent as it is better understood from the following description, which, taken in connection with the accompanying drawings, discloses a preferred embodiment thereof.

Referring to the drawings:

Figure 1 is a fragmentary top plan view of a feeding mechanism embodying the present invention;

Fig. 2 is a horizontal sectional detail of the testing station shown in Fig. 1, with parts broken away;

Fig. 3 is a longitudinal vertical section taken substantially along the line 3—3 in Fig. 1, with parts broken away;

Fig. 4 is an enlarged transverse vertical section taken substantially along the broken lines 4—4 in Fig. 1, with parts broken away, the view showing a single sheet of standard thickness passing between elements of the gauging device;

Fig. 5 is a view similar to Fig. 4 with the gauge parts in a different position and showing fragmentary portions of two stuck-together sheets interposed between the gauging elements; and

Figs. 6 and 7 are fragmentary vertical sectional views taken substantially along the respective section lines 6—6 and 7—7 in Figs. 4 and 5 with parts broken away.

As a preferred embodiment of the invention the drawings illustrate the principal parts of a feeding mechanism for advancing flat sheets or blanks into and through a can making machine for converting the blanks into can or container parts. In such a feeding mechanism the blanks, indicated by the letter A, are fed in a continuous procession and in an intermittent or step-by-step manner along a predetermined path of travel which includes a testing or gauging station.

While a blank A is at rest at the testing station 25 it is subjected to a testing operation for detecting sheets of abnormal thickness. The term abnormal, for the purpose of this specification, will be used to denote sheets or blanks that are thicker than a predetermined normal thickness or sheets 30 that are stuck together, as double sheets, in which their combined thickness is greater than the normal. Thinner sheets or blanks will not be tested by this mechanism.

The blanks to be tested are advanced through 35 the machine by a pair of spaced and parallel reciprocable feed bars 11 (Figs. 1 and 3) which slide in longitudinal grooves 12 formed in a horizontal slide plate 13 secured to a table 14 of a frame 15 which may constitute the main frame 40 of the machine. The feed bars carry a plurality of spaced depressible feed fingers or dogs 16 which engage behind the blanks.

The blanks are supported in a horizontal position on top of the feed bars 11 and on end guide 45 rails 18 which are secured to the table 14. The rails extend in parallel relation along the feed bars.

The feed bars 11 are reciprocated in unison through a forward or feeding stroke and thence 50 through a return stroke by an upright actuating lever 21 which is mounted, at its lower end, on a pivot pin 22 carried in bearings 23 formed on the main frame 15. The upper end of the lever is connected by a link 24 to a cross-head 25 55 which is secured to the feed bars and which ties

them together. The cross-head extends down through and operates in openings 26 formed in the slide plate 13 and in the frame table 14.

The actuating lever 21 is rocked in time with the other moving parts of the machine by an eccentric arm 28, one end of which is connected to the lever intermediate its ends. The opposite end of the eccentric arm is formed with an eccentric strap 29 which surrounds an eccentric 31 mounted on a cross-shaft 32 journaled in bearings 33 formed on the main frame 15. The shaft 32 constitutes the main driving shaft and may be rotated in any suitable manner.

On the forward stroke of the feed bars 11, the feed fingers 16 progressively advance the blanks through the various working and idle stations of the machine. On the return stroke of the feed bars the blanks are held against return movement by depressible hold back fingers 35 which are located in a pair of stationary hold back bars 36 disposed adjacent and parallel with the feed bars. The hold back bars are seated in longitudinal grooves 37 formed in the slide plate 13. It is during these return strokes of the feed bars, while the blanks are momentarily at rest, that the testing of a blank is brought about.

The testing of the blanks for abnormal thickness is performed on a predetermined area on the surface of each blank, preferably near one edge or end thereof, and is effected by a testing or gauging device located adjacent the path of travel of the blanks. The gauging device comprises a rotary actuating gauge disc 38 and a pivotally mounted detector element or lever 42 (Figs. 4 and 5). The rotary gauge disc is located above and at one side of the path of travel of the sheets. The gauge disc is mounted on a shaft 43 which is journaled in a bearing 44 of a bracket 45 secured to the table 14.

The rotary disc 38 is formed with a cam shaped contour or periphery which includes a full diameter or enlarged gauging section 46 (Figs. 4 and 5) and a reduced diameter or clearance section 47. The reduced section permits passage of the blanks to and from their gauging position as they advance along their path of travel.

Disc 38 is continuously rotated in time with the other moving parts of the machine and in time with the advancement of the blanks, by a bevel gear 48 which is mounted on the gauge shaft 43. The gear 48 meshes with and is driven by a bevel gear 52 mounted on a short cross shaft 53 journaled in bearings 54, 55 of the bracket 45. The shaft is rotated by a bevel gear 56 mounted on this shaft.

The bevel gear 56 meshes with and is driven by a bevel gear 57 mounted on a stub shaft 58 journaled in a bearing 62 of the bracket 45. The stub shaft 58 is rotated by a sprocket 63 (Fig. 3). This sprocket is driven by a chain 64 which operates over a driving sprocket 65 mounted on a jack shaft 66 journaled in bearings 67 formed in a bracket 68 mounted on the main frame 15. The jack shaft 66 carries a bevel gear 72 which meshes with and is driven by a bevel gear 73 mounted on the main drive shaft 32. Thus the operation of the rotary gauge is synchronized with the operation and movement of the feed bars 11.

The detector element 42 (Figs. 4 and 5) is disposed adjacent the rotary gauge member 38 and comprises a lever member mounted on a pivot stud 74, carried in a pair of spaced and parallel bearing lugs 75 (Fig. 2) formed on the inner end of a carrier plate 76 bolted to the bot-

tom of the bracket 45. The bearing lugs are disposed in an opening 77 formed in the adjacent guide rail 18 along which the blanks travel and on which they are supported when they are at rest at the testing station or when they are passing through the testing station.

The detector lever 42 is formed with a short anvil leg 78 which extends inwardly and under the path of travel of the sheets substantially at right angles thereto and at a locality just below the rotary gauge member (Fig. 6). This anvil leg is disposed in the opening 77 in a guide rail 18, with the top surface of the anvil leg disposed substantially flush with the blank supporting surface of the guide rail. The lever member is also formed with an extension or movement multiplying arm 79 which extends away from the blanks and is disposed in a recess 80 in the bottom of the bracket 45.

In the normal position of the detector 42, as best shown in Fig. 4, the top face of its inner or anvil end 78 just clears the bottom surface of the blanks as they pass thereover, while the outer arm 79 engages against a stop pin 81 which is secured in the carrier plate 76. A spring pressed plunger 82 disposed in a vertical bore in the bracket 45 and located above the lever arm 79, yieldably holds the lever in this position. In this normal position the outer end of the lever arm 79 engages against a movable element 83 of a normally closed electric switch 84 bolted to the bracket 45.

In operation, the space between the gauging section 46 of the rotating gauge member 38 and the top face of the anvil leg 78 of the detector 42 is equal to the thickness of a normal blank. Hence when a normal thickness blank momentarily stops at the testing station, the rotating disc 38 just clears the blank, as shown in Figs. 4 and 6, and nothing happens. Such a blank is permitted to advance further through the machine on the succeeding feed stroke of the bars 11.

When an abnormal thickness blank or when two or more blanks are stuck together and are advanced into position at the gauging station, the enlarged or gauging section 46 of the rotating gauge member 38 strikes the top of the blank or blanks and deflects or forces a portion of the same down into the opening 77 of the guide rail 18 as shown in Figs. 5 and 7. This deflection of the abnormally presented blank or blanks is very slight and takes place at the cut-away edge of the guide rail adjacent the opening 77, the rail edge acting as a fulcrum so that these portions of the blanks are moved out of the supporting plane of the guide rail and are pressed down against the anvil leg 78 of the detector lever. This rocks the lever and lifts its outer arm 79 against the resistance of the spring plunger 82. Lifting of the outer arm of the detector lever presses the movable element 83 of the electric switch 84 inwardly and thus opens the switch.

The electric switch 84 is part of a motor circuit C (Fig. 4) which includes a machine driving motor 85 and a source of electric energy such as a generator 86 as indicated in the wiring diagram of Fig. 4. Electric energy from the generator normally flows through the circuit along a wire 87, motor 85, a wire 88, switch 84, wire 89, normally closed service switch 91, and returns to the generator by a wire 92. When this circuit is broken by the opening of the switch 84, the motor 85 stops. This stops the machine. The machine will remain inoperative until the abnormal blanks are removed manually from the

gauging station. Upon removal of the abnormal blanks, the detector lever returns to its normal position, and this closes the electric switch 84 so that operations may be again resumed.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a mechanism for gauging sheets to detect abnormal thickness, the combination of a stationary guide along which sheets are advanced for gauging, a movable detector located on one side of said guide adjacent the path of travel of a said sheet and having a part extending into sheet gauging position, a rotary gauge having a fixed axis located on the opposite side of the path of travel of said sheet and having an enlarged peripheral section spaced from said guide a distance equal to a normal thickness sheet when said peripheral section moves into sheet gauging position, the peripheral section of said gauge deflecting an abnormal thickness sheet while in said gauging position and moving said detector, and means operated by said detector when it moves for indicating the presence of such an abnormal sheet.

2. In a mechanism for gauging sheets to detect abnormal thickness, the combination of a feed table for supporting advancing sheets to be gauged, a pivotal detector lever located adjacent said table and having a leg at one end in sheet gauging position, and having an extension arm at the other end, a rotary gauge having a fixed axis located opposite said detector lever so that the advancing sheets pass between the gauge and leg, said gauge having an enlarged peripheral section spaced from said detector lever a distance equal to a normal thickness sheet when said peripheral section moves into sheet gauging position, the peripheral section of said gauge deflecting an abnormal thickness sheet passing said gauging position and moving the leg of said detector lever, and means engageable by said extension arm upon movement of said detector lever for indicating the presence of such abnormal sheet.

3. In a mechanism for gauging sheets to detect abnormal thickness, the combination of a stationary guide along which sheets are advanced intermittently for gauging, a movable detector located on one side of said guide adjacent the path of travel of a said sheet, a rotary gauge having a fixed axis located on the opposite side of the path of travel of said sheet and having

enlarged and reduced peripheral sections, said enlarged section being spaced from said guide a distance equal to a normal thickness sheet when it moves into sheet gauging position opposite said

5 detector and when a sheet being gauged is at rest to deflect an abnormal thickness sheet against said detector to move the latter, said reduced section providing clearance for the sheets advancing into and out of gauging position, and
10 10 means operated by said detector when it moves for indicating the presence of such abnormal sheet.

4. In a mechanism for feeding and gauging sheets to detect sheets of abnormal thickness, the
15 combination of a feed table for supporting the sheets, a feeding device operable along said table for intermittently advancing the sheets, a detector lever located in said table and having an anvil leg at one end with an engageable surface disposed in the plane of the table top, a continuously rotatable shaft located above said table top, means for operating said feeding device and said gauge shaft in synchronism, a disc gauge mounted on said shaft and having a gauging section projecting beyond its normal periphery and moving opposite the engageable surface of said detector anvil leg with a space therebetween equal to a normal thickness sheet, an abnormal thickness sheet being moved in part out of the
20 normal path of travel of the sheets and against the engageable surface of said leg by said disc gauge thereby shifting said detector lever, and a stop device located adjacent said detector lever and operable by the movement thereof for nullifying said operating means to stop further feeding of said sheets when such an abnormal thickness sheet is encountered.

5. In a mechanism for feeding and gauging sheets to detect abnormal thickness, the
25 combination of a feed table for supporting the sheets, a detector lever located in said table, a feeding device operable along said table for successively advancing the sheets in processional order past said detector lever, a rotatable disc gauge located
30 above said table and having a gauging section moving in spaced relation to said detector lever at a distance substantially equal to a normal thickness sheet, means for continuously rotating said disc independently of and in synchronism with the advancement of the sheets relative thereto, said disc being engageable with and adapted to deflect an abnormal thickness sheet against said detector lever to move the same, an electric circuit including electric means for operating said
35 feeding device and said gauge, and an electric switch connected into said electric circuit and operable by said detector lever to break said circuit to stop the operation of said feeding device until the abnormal sheet is removed.

60 WILLIAM PECHY.
